UNITED STATES PATENT OFFICE

THOMAS D. SCHAADT, OF FULLERTON, PENNSYLVANIA

DESIGN FOR A CABINET

Application filed July 16, 1931. Serial No. 40,574. Term of patent 3½ years.

To all whom it may concern:

Be it known that I, THOMAS D. SCHAADT, a citizen of the United States, residing at Fullerton, county of Lehigh, State of Pennsylvania, have invented a new, original, and ornamental Design for a Cabinet, of which the following is a specification, reference being had to the accompanying drawing, forming part thereof.

The figure is a front elevational view of a cabinet showing my new design.

The depth of the cabinet is conventional.

I claim:

The ornamental design for a cabinet as shown and described.

In testimony whereof I hereunto affix my signature.

THOMAS D. SCHAADT.
